Gifford & Scull ATTORNEYS

UNITED STATES PATENT OFFICE

DAVID S. JACOBUS, OF MONTCLAIR, NEW JERSEY, ASSIGNOR TO THE BABCOCK & WILCOX COMPANY, OF BAYONNE, NEW JERSEY, A CORPORATION OF NEW JERSEY

AIR HEATER

Application filed November 3, 1927. Serial No. 230,737.

This invention relates to an air heater and is a division in part of my application Serial No. 571,919, filed June 30, 1922 which has matured into Patent #1,647,997, dated November 8, 1927. The invention will be understood from the description in connection with the accompanying drawings, in which Fig. 1 is a vertical section through an illustrative embodiment of the invention; Fig. 2 is a perspective view on an enlarged scale showing some of the details; Fig. 3 is a vertical section through a modification; and Fig. 4 is a perspective view showing some of the details of Fig. 3.

In Fig. 1, I have illustrated a steam boiler 5 of the well known type, the hot gases from which pass through a gas outlet 6 and downwardly over an economizer 7 into a flue 8. From this flue, the hot gases pass upwardly through a flue 9 around the air heater, which is to be described more specifically hereinafter, passing at the top through a cross flue 10 which may be of the form illustrated, and then downwardly through a vertical flue 11 to a gas outlet flue 12 which is connected, in the form illustrated to a fan 13 by which the gases are forced to a stack 14.

A fan 15 forces air through a flue 16 into the air heater, the air flowing upwardly through the ducts of the air heater and then across a horizontal connection, which will be described more fully hereinafter, into the second set of air ducts through which the air passes downwardly to an air outlet flue or duct 17 from which it may be supplied to a combustion chamber through an underfeed stoker 18, which I have adopted for purposes of illustration.

In the form illustrated, as more clearly shown in Fig. 2, the air ducts are formed of metallic sheets placed side by side with the spaces between their edges closed to form gas-tight joints. In the form illustrated in Fig. 2, each duct is made up of a flat sheet metal plate 20 and a similar plate 21 having its edges bent, as shown at 22 and 23, to provide a spacing portion and a fastening portion, the portion 23 being riveted to the edges of the plate 20, as shown at 24. This construction forms flat tubes spaced apart. Each tube is formed

by two plates spaced apart a distance that is small in proportion to the width of the plates and the width is small in proportion to the length. The spaces between such tubes form passages which are similar in shape and general proportions to the tubes. The spaces between the upper ends of pairs of plates 20 and 21 are closed by horizontal strips 25 and the spaces between these strips 25 are left open. Alternate spaces between the lower beveled ends of the plates 20 and 21 are closed by inclined closure members 26, so that the closures 25 and 26 at opposite ends of the plates are staggered with respect to each other. The spaces between the plates 20 and 21 in the respective ducts 9 and 11 are closed by strips 27 along the central plane of the air heater and alternate spaces between these plates 20 and 21 are left open for a short distance below the strips 25 so that air can pass below the strips 25 from one duct 11 to the other duct 9.

The spaces between the edges of the plates 21 and 22 near the lower ends are left open for some distance, as shown at 28, corresponding to the open spaces between the strips 25 at the top, so that gases enter the air heater near the lower end between alternate plates in a direction substantially parallel to the longitudinal axis of the ducts and pass between the strips 25 into the cross flue 10, thence downwardly between corresponding plates in the duct 11, and thence outwardly through the spaces 28. A pocket 29 (Fig. 1) below the outlet 8 is so located and shaped as to provide a reverse bend for the gases, with the result that the gases enter the heater in such a direction that they will be well distributed across the spaces between the plates without crowding too much to one side and leaving inactive portions. The gases flowing downwardly over the economizer 7 and through the flue impinge against the lower inclined wall of the dust hopper 29 and are deflected upwardly in such a way that the gas stream makes a less angle with the longest center line of the passageway in the fluid heater than does the inclined wall opposite the opening through which the gases enter. As the gases flow upwardly from the bottom 100

of the hopper 29, they assume a generally fan-shaped form, the axis of which more nearly approach the longest center line of the heater than does the wall opposite the entrance opening. This construction causes the gases to be evenly distributed across the passages from front to rear of the air heater. It will be apparent that where the gases are introduced at a right angle to the longest axis of the air heater, then the gases pile up against the wall opposite the opening against which the gases are introduced, with the result that there is an unequal distribution of the mass flow of the gases through different portions of the passage which leads to a less efficient heat transfer than in the case of applicant's device where the gases are evenly distributed. Also the air entering through the inlet 16 is traveling in the direction it will take in passing through the spaces in the duct 11.

In the modification shown in Figs. 3 and 4, the gases from the economizer 7 pass through the pocket 29' and thence enter the air heater 30 that is provided with horizontally extending spaced plates, as shown in detail in Fig. 4. The upper and lower edges of the plates 31 and 32 are bent so as to contact with each other, as shown at 34, in pairs, thus leaving spaces between the pairs for the passage of the hot gases and spaces between the plates of the pairs for the passage of air to be heated. The hot gases are caused to enter in the direction of the longitudinal axis of the air heater, so that there is good distribution of gases without crowding to one side and the air is also caused to enter in a similar manner from the other end of the air heater. The spent gases pass out through spaces 35 on one side at one end of the air heater and the heated air passes out through spaces 36 along the opposite side at the other end of the air heater.

I claim:

1. In an air heater, flat tubes and spaces between them forming passageways for air and a heating gas, respectively, means for directing one of the fluids into said passageways substantially in the direction of the longest center line of said passageways, and an inlet opening for the other fluid in the side of the heater, the wall of said heater opposite said opening being inclined to said longest center line, the angle between the stream flow of the other fluid through said opening and said longest center line of said heater being less than that between said wall and said longest center line.

2. In an air heater, flat tubes and spaces between them forming passageways for air and a heating gas, respectively, means for directing one of the fluids into said passageways substantially in the direction of the longest center line of said passageways, an inlet opening for the other fluid in the side of the heat-

er, the wall of said heater opposite said opening being inclined to said longest center line, the angle between the stream flow of the other fluid through said opening and said longest center line of said heater being less than that between said wall and said longest center line, and means to cause the gas and air to flow in countercurrent directions through their respective passageways. 70

3. In an air heater, flat tubes and spaces between them forming passageways for air and a heating gas respectively, means for directing one of said fluids into its passageways in the direction of the longest center line of said passageways and an inlet opening for the other fluid in the side of the heater, the wall of said heater opposite said opening being inclined to said longest center line, the angle between the stream flow of the other fluid through said opening and said longest center line of said heater being less than that between said wall and said longest center line, with said fluids flowing countercurrent. 80

4. In an air heater, flat tubes and spaces between them forming passageways for air and a heating gas, respectively, means for directing one of said fluids into its passageways in the direction of the longest center line of said passageways and an outlet opening for the other fluid in the side of the heater, the wall of said heater opposite said opening being inclined to said longest center line, the angle between the stream flow of the other fluid through said opening and said longest center line of said heater being less than that between said wall and said longest center line, with said fluids flowing countercurrent. 90

5. In an air heater, flat tubes and spaces between them forming passageways for air and a heating gas, respectively, means for directing one of said fluids into its passageways in the direction of the longest center line of said passageways and means for directing the other fluid into its passageways substantially in the opposite direction along said center line, with said fluids flowing countercurrent, said last named means comprising a pocket located near the entrance to said passageways. 100

6. In an air heater, flat tubes and spaces between them forming passageways for air and a heating gas, respectively, means for directing one of the fluids into said passageways substantially in the direction of the longest center line thereof, and means comprising a dust hopper located in the flue approaching said air heater for deflecting the stream flow of the other fluid and causing it to enter the air heater substantially in the direction of the longest center line of said passageways. 110

7. In an air heater, flat tubes and spaces between them forming passageways for air and 120

a heating gas, respectively, means for directing one of the fluids into said passageways substantially in the direction of the longest center line thereof, and an inlet opening for the other fluid in the side of said heater, the wall of the heater opposite said opening being inclined to said longest center line, the angle between the stream flow of the other fluid through said opening and said longest center line of said heater being less than that between said wall and said longest center line.

8. In an air heater, flat tubes and spaces between them forming passageways for air and a heating gas, respectively, means for directing one of the fluids into said passageways substantially in the direction of the longest center line of said passageways, means for directing the gases over the heating surface of a steam boiler and then through an inlet opening in the side of the heater, the wall of the heater opposite said opening being inclined to said longest center line, and a soot hopper located in the portion of the flue where the passages approach the air heater for directing the gas stream flow substantially in the direction of the longest center line of said passageways.
